UNITED STATES PATENT OFFICE.

WILLIAM WARNICK AND HENRY L. LEILICH, OF DELPHOS, OHIO.

DESIGN FOR A BROODER-COOP.

45,774.

Specification for Design.

Patented May 12, 1914.

Application filed December 13, 1912. Serial No. 736,623. Term of patent 7 years.

To all whom it may concern:

Be it known that we, WILLIAM WARNICK and HENRY L. LEILICH, citizens of the United States, and residents of Delphos, in the county of Allen and State of Ohio, have invented a new, original, and ornamental Design for a Brooder-Coop, of which the following is a specification, reference being had to the accompanying drawing forming part thereof.

The figure is a front perspective view of a brooder coop, showing our new design.

We claim:

The ornamental design for a brooder coop, as shown.

WILLIAM WARNICK.
HENRY L. LEILICH.

Witnesses:

J. D. BRENNEMAN,
JOHN F. LINDEMANN.
